UNITED STATES PATENT OFFICE.

LEO GINZBOURG, OF JERSEY CITY, NEW JERSEY.

RANGE-FINDER.

1,398,853.

Specification of Letters Patent. Patented Nov. 29, 1921.

Application filed December 1, 1919. Serial No. 341,583.

To all whom it may concern:

Be it known that I, LEO GINZBOURG, a citizen of the United States, and a resident of Jersey City, in the county of Hudson and State of New Jersey, have invented a new and Improved Range-Finder, of which the following is a full, clear, and exact description.

The present invention relates to new and useful improvements in range finders, and it pertains more particularly to a device especially adapted for finding the distance of objects in order that a camera may be properly focused.

It is the primary object of the invention to provide a small portable device by means of which the distance of objects may be ascertained.

Referring to the drawings—

Figure 1 is a side elevation of the device showing the manner of its use;

Fig. 2 is a vertical sectional view on a reduced scale;

Fig. 3 is a detail sectional view on an enlarged scale.

Referring more particularly to the drawings, the device comprises an arcuate plate 5, which is preferably formed of metal, it being understood, however, that other material may be used if desired. The metal plate 5 is provided on one of the corners of its peripheral edge with a sighting element 6, which is formed by continuing the peripheral edge beyond the side edge of the arcuate plate. The reference character 7 designates a second sighting element in line with the first sighting element 6, said sighting element 7 being positioned at the apex of the arcuate plate 5. Adjacent the sighting element 7, the arcuate plate 5 is provided with an opening 8, and passing through said opening 8 is a cord 9, the inner end of which is provided with a nut 10, by means of which the cord is retained within the opening. The cord 9 projects beyond the peripheral edge of the arcuate plate 5 and is provided on its free end with a weight 11.

The plate 5 is provided near its peripheral edge with two openings 12, and secured within said openings 12, is a flexible guide member 13, which is spaced from the face of the plate, as indicated by the reference character 14. This resilient guide member 13 is curved to conform to the curvature of the peripheral edge of the plate 5, and has its ends bent at right angles to the body por-

tion, as indicated by the reference character 15. Subsequent to the bending of the ends 15, they are folded upon themselves as indicated by the reference character 16, to retain them in place relative to the plate 5. The cord 9 is adapted to occupy a position behind this flexible guide 13, and said guide serves the means by which the cord is maintained in contact with the plate 5 during the operation of the device.

In addition to forming a guide for the cord 9, the member 13 serves as means by which the cord may be retained in any position it may occupy relative to the plate 5, by exerting a slight pressure on said member 13. This slight pressure exerted on the member 13 pinches the cord 9 against the plate 5 in order that it may be retained in the position which it occupies when obtaining a reading.

In use, the two sighting elements 6 and 7 are brought in a line with each other and are in turn lined up with the base of the object whose distance it is desired to ascertain. This operation causes the cord 9 to swing relatively to the arcuate plate 5.

When the above recited operation has been completed, the operator grasps the peripheral edge of the plate 5 between the thumb and fore-finger and exerts a slight pressure on the guide member 13, which carries the cord 9 between itself and the plate 5.

The device is now lowered from the eye in order that a reading may be obtained, the guide 13 serving to retain the parts in the position which they assume during the sighting operation.

The arcuate plate 5 is provided around its peripheral edge with a scale 18 marked in the degrees of a circle, which, however, forms no particular part of the present invention. The plate 5 is provided on its face with a chart B, and said chart consists of a plurality of concentric curved lines which divide a portion of the plate into curved spaces. These curved spaces are each divided by radial lines into squares, and in said squares are marked the designation giving the distance reading as determined by actual measurements. For example, if a person be six feet tall, and the device is operatively positioned as shown in Fig. 1, that square which the cord 9 crosses in the column marked "6" would indicate the distance between the object and the position at which the person is standing. If, however,

the person be five feet two inches tall, that square in the column "5" which the cord intersects will give the distance between the person and the object.

5 From the foregoing it will be apparent that the present invention provides a small portable device in which the distance between two points may be ascertained with sufficient accuracy to enable the proper functioning of a camera for the purpose of taking pictures.

Claims:

1. A device of the character described comprising a plate, a weighted member 15 movable across the plate, and means carried by said plate and conforming to one of the edges thereof for guiding the weighted mem-

ber in its movement across the plate, said guiding means being capable of movement into engagement with the weighted member 20 to retain the same against movement relative to the plate.

2. A device of the character described comprising a plate, a guide member carried by the plate and conforming to one of the 25 edges thereof, said guide member being arranged in spaced relation to said plate, and weighted means movable across the space between the plate and guide member, said guide member being capable of movement 30 toward the plate to retain the said weighted means against movement.

LEO GINZBOURG.
